UNITED STATES PATENT OFFICE

130,063

DESIGN FOR AN EMBLEM PIN

Edward S. Chandler, Valley Stream, N. Y.

Application September 12, 1941, Serial No. 103,316

Term of patent 3½ years

To all whom it may concern.

Be it known that I, Edward S. Chandler, a citizen of the United States of America and a resident of Valley Stream in the county of Nassau and State of New York, have invented a new, original, and ornamental Design for an Emblem Pin, of which the following is a specification, reference being had to the accompanying drawing, forming a part thereof.

In the drawing:

The drawing is lined to show contrasting color.

I claim:

The ornamental design for an emblem pin, as shown and described.

EDWARD S. CHANDLER.
